(57) **CLAIM**

The ornamental design for a wireless earphone, as shown and described.

DESCRIPTION

1. Wireless earphone

1.1 : Perspective

1.2 : Front

1.3 : Back

1.4 : Left

1.5 : Right

1.6 : Top

1.7 : Bottom

1.8 : Reference

Reproduction 1.8 is a reference view showing a state of use in which the wireless earphone is inserted into an ear. The broken line showing of the ear in Reproduction 1.8 forms no part of the claimed design.

1 Claim, 8 Drawing Sheets(56)
